UNITED STATES PATENT OFFICE.

ANNIE CECELIA KNOWLSON, OF ANN ARBOR, MICHIGAN.

NOSTRIL-EXPANDING DEVICE.

1,014,758.

Specification of Letters Patent.

Patented Jan. 16, 1912.

Application filed May 1, 1911. Serial No. 624,343.

To all whom it may concern:

Be it known that I, ANNIE CECELIA KNOWLSON, of the city of Ann Arbor, in the State of Michigan, one of the United States 5 of America, have invented certain new and useful Improvements in Nostril-Expanding Devices, of which the following is the specification.

My invention relates to improvements in 10 nostril expanding devices, and the object of the invention is to produce a device of this class, which will facilitate easy breathing especially when asleep, and thus do away with conditions brought about by nasal ob- 15 struction and prolapse.

My invention consists of a spring member comprising a front bar terminating at each end in a coil from which extends an upwardly projecting portion on the end of 20 which is affixed a button with a soft pad on the outside and a looped wire extending from the button downwardly, then upwardly again and terminating in an outer button having a pad on the inside and designed to 25 coact at each side with the first mentioned button, so as to grip the mucous-membrane and cuticle of the nose, the parts being arranged and constructed in detail as hereinafter more particularly explained.

30 Figure 1, is a perspective view showing my improved nostril expanding device in position in the nose. Fig. 2, is a perspective detail of the nostril expanding device.

In the drawings like letters of reference 35 indicate corresponding parts in each figure.

A is a wire spring member, which is in the form shown in Figs. 1 and 2 and has a central bar A' terminating in coils A² having upwardly projecting portions A³ A³, 40 which extend into a button A⁴ of any suitable form with a rim A⁵ within which is held a pad A⁶ of comparatively soft material, such as cork. It will be noticed that the pad is on the outside. From the but- 45 ton A⁴ the wire extends downwardly in loop form A⁷ and then upwardly preferably above the level of the button A⁴ at which point a supplemental minor button A⁸ is

provided having a soft inner pad A⁹ fitting within the rim A¹⁰. This pad may be also 50 of cork or other suitable material. The object of having the pad of soft material is because it is designed to be pressed against the mucous-membrane of the nose.

To insert the nostril expander in position 55 it is merely necessary to spread apart the button A⁸ from the button A⁴ with the thumb and fore-finger of each hand then insert it into the nose, and then release the buttons when they will spring inwardly of 60 their own tension and securely grip the cuticle and mucous-membrane of the nose, and hold such nostrils apart sufficiently far to provide for easy breathing, and prevent the walls of the nostrils collapsing. The re- 65 silency of the nostril expander keeps these walls out as the spring pressure is outwardly.

The nostril expander may be readily ad- 70 justed at different widths of nostrils by bending the bar A', so as to bring the but- 75 tons close together.

What I claim as my invention is:

1. A nostril expanding device comprising a spring member or wire having a central 75 cross bar terminating in coils and extending upwardly at each end and provided with a button and then downwardly in the form of a loop and then upwardly at each end and provided with a terminal button at each end 80 as and for the purpose specified.

2. A nostril expanding device comprising a spring member or wire having a central cross bar terminating in coils and ex- 85 tends upwardly at each end and provided with a button and then downwardly in the form of a loop and then upwardly at each end and provided with a terminal button, the inner button at each side being provided with an outer pad and the outer button at 90 each side with an inner pad as and for the purpose specified.

ANNIE CECELIA KNOWLSON.
